UNITED STATES PATENT OFFICE

CHARLES P. KIMMEL, OF GARY, INDIANA

RAILROAD CROSSING

Application filed January 20, 1932. Serial No. 587,735.

My invention relates to a construction adapted for use at the intersection of highways with railroad tracks.

Under modern traffic conditions such crossings have certain very definite requirements due to the high speed and weight of vehicles using the highways and the necessity for constant maintenance to provide a relatively smooth surface. An object of this invention is to provide a crossing structure of relatively low initial cost that may be installed by ordinary track labor with tools as generally carried by the ordinary railroad section gang and that may easily be maintained without excessive cost or extensive interruption of highway traffic.

Some of the requirements of an ideal crossing structure are as follows:

First: The crossing section must be the full depth of the rail.

Second: It must have sufficient mass to resist high speed impact.

Tenth: It shall be so designed that it may be applied without special construction work to curves, frogs and switches.

Eleventh: It shall adapt itself to varying rail heights without the necessity for a corresponding number of different production rolls and preferably it shall be adapted to utilize standard sections in order to meet different rail height conditions.

Twelfth: The construction shall be such that when assembled it will drain water away from the road bed directly beneath the crossing.

The construction hereafter described meets the conditions referred to in every particular.

The invention will be more readily understood by reference to the accompanying drawings, in which:

Fig. 1 is a transverse sectional view through a single crossing constructed in accordance with my invention;

Fig. 2 is a plan view of the end portion thereof and

by railroads. The toe of the base section will extend forward sufficiently so that when resting upon the tie plate flange, tipping of the fabricated section will not be possible. If the tie plate flange is thinner than the height of the recess 15, a slight adzing of the tie beneath the foot flange 14 of the base section will allow the toe of the base section to rest upon the tie plate flange.

- 10 The body or leg 16 of the toe angle is shaped to provide a seat for the marginal edge of the stem 17 of the T section, the stem of the T section being joined to the upright leg of the base section by rivets 18, as shown, or by spot welding, if desired. A T section will be selected having suitable dimensions in order that the height when riveted in place will correspond to the height of the track rail. If desired of course the upper surface of the flange or table 19 of the T section may be recessed or indented as at 20 to provide anti-skid surfaces.
- 15 20 At the ends, portions of the T sections 17 are cut away, preferably as indicated at 21 in Fig. 3 and the end portion of the flange 19 bent downward to provide a foot 22 through which a spike 23 may be driven into the tie. This provides an inclined upper surface or approach to the crossing that will avoid possibility of catching on dragging brake beams or rods.

- 25 30 At the ends, portions of the T sections 17 are cut away, preferably as indicated at 21 in Fig. 3 and the end portion of the flange 19 bent downward to provide a foot 22 through which a spike 23 may be driven into the tie. This provides an inclined upper surface or approach to the crossing that will avoid possibility of catching on dragging brake beams or rods.
- 35 The space between the assembled fabricated section is filled with vehicle track material such as indicated at 24. This may be bituminous or stone and a binder of a suitable kind. I may prefer to install a pair of fabricated sections between the fabricated sections adjacent to the track rails as shown in Fig. 1 in which case a tie plate is laid on the tie in order 40 to provide a construction identical to that adjacent to the track rails.

- 45 The base leg of the toe angle necessarily has to be of a length to give adequate upright support and allow for efficient spiking to the cross ties. It is obvious that the base angle section as shown on the drawings would resist bending about a curve or radius of the track. A slot 25 is sawed to a certain depth into the base leg of the toe angle at intervals 50 that will allow the section to be formed about a curve by the ordinary track gang without any special bending equipment. It is obvious that if it was required to form the assembled sections at the point of fabrication to suit the many different degrees of curvatures that obtain, it would be a great inconvenience and expense.

- 55 It will be noted that the crossing may be installed by the ordinary track gang; that it may be painted or coated from time to time by removal of the material 24; that the material adjacent to the track rail may be readily removed for inspection of bolts and fish plates and that the crossing structure is in effect a unit with the track structure.

Modifications in the structure may suggest themselves to those skilled in the art and I do not wish to be limited except as indicated in the appended claims.

I claim:

- 70 75 80 85 90 95 100 105 110 115 120 125 130 1 1. In a railroad crossing, the combination with the track rails, ties and tie plates, of a pair of guard rails spaced a suitable distance from and extending parallel to the track rails for the length of the crossing, said guard rails being of generally T-section, formed in two parts that are joined through their webs, the lower part having a foot flange adapted to overlie the tie-plates and be spiked to a tie.
2. In a railroad crossing, the combination with the track rails, tie and tie plates, of a pair of guard rails spaced a suitable distance from and extending parallel to the track rails for the length of the crossing, said guard rails being of generally T-section, formed in two parts that are joined through their webs, the lower part having a foot flange adapted to overlie the tie-plates and be spiked to a tie, the upper part being in the form of a standard T-section the depth of the web of which may be selected to produce a guard rail of the same height as the track rail.
3. In a railroad crossing, the combination with the track rails, tie and tie plates, of a pair of guard rails spaced a suitable distance from and extending parallel to the track rails for the length of the crossing, said guard rails being of generally T-section, formed in two parts that are joined through their webs, the lower part having a foot flange adapted to overlie the tie-plates and be spiked to a tie, and readily removable vehicle-track material for filling the crossing to rail height between adjacent guard rails.
4. A fabricated element for railroad crossings, comprising a two part section, the parts being joined through lapped webs, the lower part being formed to provide a foot flange to overlie a tie-plate and to be spiked to a tie, the upper part having a flange, the upper surface of which is adapted to lie in the plane of the top of a track rail.
5. A fabricated element for railroad crossings, comprising a two part section, the parts being joined through lapped webs, the lower part being formed to provide a foot flange to overlie a tie-plate and to be spiked to a tie, the upper part being a standard T-section, the dimensions of which may be selected to produce a guard rail corresponding in height to the track rail with which it is to be used.
6. A fabricated element for railroad crossings, comprising a two part section, the parts being joined through lapped webs, the lower part being formed to provide a foot flange to overlie a tie-plate and to be spiked to a tie, said lower part being standard for all track rail heights, the upper part being a standard

T-section of varying heights to correspond to the track rail height.

7. A fabricated element for railroad crossings, comprising a two part section, the parts being joined through lapped webs, the lower part being formed to provide a foot flange to overlie a tie-plate and to be spiked to a tie, the upper part having a flange, the upper surface of which is adapted to lie in the plane of the top of a track rail, the web of the upper part being cut away at the ends and the flange bent diagonally down in position to be spiked to a tie.

In testimony whereof I have affixed my
15 signature.

CHARLES P. KIMMEL.
